UNITED STATES PATENT OFFICE.

JOHN F. STRAITZ, OF PHILADELPHIA, PENNSYLVANIA, ASSIGNOR TO NATIONAL AIR-OIL BURNER COMPANY, OF PHILADELPHIA, PENNSYLVANIA, A CORPORATION OF DELAWARE.

FLUID-CONTROL COCK.

Application filed May 7, 1920. Serial No. 379,647.

My invention relates to improvements in fluid control cocks. The object is to provide improved means for regulating or controlling the flow of fluid.

5 The invention is especially adapted for such control in connection with oil or hydrocarbon burners.

The invention comprises means for preventing the leak of fluid from the device, 10 for preventing clogging in the passages thereof, for securing precise and accurate regulation of the flow therethrough, and for indicating the adjustment or control of such flow.

15 Referring to the drawings, which illustrate merely by way of example, a suitable embodiment of my invention:—

Fig. 1 is a plan view.

Fig. 2 is a section on line 2—2 of Fig. 1.

20 Fig. 3 is a diagram relating to the method of regulation.

Similar numerals refer to similar parts throughout the several views.

Referring especially to Fig. 2, the housing 5 is preferably an integral body having the intake port 6 and the discharge port 7 with the intermediate channels 8 and 9. This housing 5 has a tapered opening forming a seat 10 for the plug valve 11. The 25 plug valve 11 is provided with a channel 12, having a circular cross-section corresponding to the circular cross-sections of channels 8 and 9. This plug 11 also has a shank 13 extending upwardly through the 30 housing and the cap 14 secured thereon. The upper end 15 of shank 13 is of angular formation and has secured thereto the operating handle 16 as shown. This operating handle 16 is provided with the split 35 formation 17 and the screw 18 for clamping the same to the square part 15 of shank 13. Handle 16 is also provided with an indicator finger or pointer 19 adapted to cooperate with the scale or graduation 20 on a plate 21 preferably formed integral with the housing 5.

The upper part of the opening of housing 5 is interiorly threaded, as at 5^a, to receive the threaded cap 14. This cap 14 is 40 interiorly recessed to receive the packing 22, the floating ring 23 and one end of the spring 24.

The plug member 11 has a countersunk or annular channel at the upper part thereof

and surrounding the shank 13 forming a 55 seat for the lower end of the spring 24.

The spring 24 is adapted to fit snugly about the round portion of shank 13 and between the top of the plug valve 11 and the underside of the floating ring 23, thereby 60 tending, when the cap 14 is screwed into place, to press the plug 11 into a tight, yet yielding fit with the housing 5, and also to force the floating ring 23 upwardly to compress the packing 22 and thus maintain the 65 same effective to prevent leak past the shank 13.

By screwing the cap 14 inwardly or outwardly with respect to the housing 5 the effectiveness of the spring is adjusted to 70 maintain the plug 11 in position of maximum efficiency and at the same time maintain the packing sufficiently compressed.

The cross-section of the channels 8, 9 and 12 are in true circles of the same diameter 75 so that a very fine adjustment may be secured of the opening or passage between ports 6 and 7 and without danger of the fluid or other agent passing therethrough becoming clogged in said passage-ways. 80 For instance an extremely fine opening may be secured as indicated in Fig. 3, where the circles overlap and thus provide an extremely nice adjustment without danger of clogging; and this makes it also possible to secure an accurate indication of such adjustment, by means of the pointer and scale 19 and 20. The lug 25 is provided on the plate 21 as a stop for limiting the movement of the valve. 90

The special advantage of the spring pressure exerted on the plug 11, to keep the same in efficient and non-leaking relation with the housing 5, is that it does not tend to cause a binding or a sticking of the plug 95 in the housing, nor does it present any means for leaking, such as the usual screw which projects through the bottom of the housing into the plug to force the plug into efficient fit. 100

I claim:

In a fluid control cock, the combination of an integral body having an inlet port and a discharge port, a cylindrical interiorly threaded open end and a tapered recess extending therefrom part way into said body between said ports, restricted channels forming communication, between said recess 105

and said ports, and a flange projecting from said body in a plane at right angles to the axis of the tapered recess, provided with graduation marks and a stop on the face thereof, a tapered valve plug fitting into said tapered recess having a channel of same diameter as that of the restricted channels and adapted to register therewith and having a spindle integral therewith and an annular recess in the top of the plug surrounding the spindle, a recessed cap threaded into said threaded end and surrounding the spindle, a packing within the cap and surrounding the spindle, a floating ring impinging the packing, a spring under compression having one end engaging the floating ring and the other end seated in the annular recess of the plug, and a handle secured to the spindle having a pointer for sweeping the graduated plate and adapted to engage the stop. 15 20

JOHN F. STRAITZ.
